UNITED STATES PATENT OFFICE.

GEORGE E. POTTER AND ELVIE L. POTTER, OF CHICAGO, ILLINOIS.

INVISIBLE TIE HOLDER.

1,413,131.

Specification of Letters Patent. Patented Apr. 18, 1922.

Application filed June 24, 1921. Serial No. 480,047.

To all whom it may concern:

Be it known that we, GEORGE E. POTTER and ELVIE L. POTTER, citizens of the United States, and residents of Chicago, in the county of Cook and State of Illinois, have invented a new and useful Improvement in Invisible Tie Holders, of which the following is a full, clear, and exact description.

Our invention relates to improvements in devices for holding a neck tie in adjusted position with respect to a shirt, and it consists in the combinations, constructions and arrangements herein described and claimed.

An object of our invention is to provide a tie holder that is adapted to hold a tie of the four-in-hand type in a desired position with respect to a shirt without being visible.

A further object of our invention is to provide a tie holder that is formed in one piece and is adapted to detachably secure a tie to a shirt while being concealed by the tie.

A further object of our invention is to provide a device of the character described that can be quickly and easily applied to a shirt and tie or detached therefrom, and which has means for preventing its accidental displacement from the shirt and tie.

A further object of our invention is to provide a device of the character described that is simple in construction, capable of being manufactured cheaply, and thoroughly practical commercially.

Other objects and advantages will appear in the following specification, and the novel features of the invention will be particularly pointed out in the appended claims.

Our invention is illustrated in the accompanying drawings, forming part of this application, in which—

Figure 1 is a view, showing the device operatively applied.

Figure 2 is a perspective view of the device, and

Figure 3 is a section through a shirt and tie, showing the holder in adjusted position with respect thereto.

In carrying out our invention, we provide a member consisting of a single piece of wire having inherent spring qualities and being bent approximately midway its length to form a pin portion 1, a spring portion 2, and a clamping portion 3. The pin portion 1 is sharpened at its end 4 and is sinuous in form adjacent to its sharpened end or point, as at 5. The clamping portion 3 is arranged

to normally contact the pin portion 1 at a point about one-third the distance to its extremity, as at 6. It is then bent laterally substantially at right angles to the pin portion 1 and then bent backwardly on itself to provide a substantially U-shaped clamping loop 7, the arms of which are normally in contact with each other adjacent to their extremities, as at 8.

In service, the pin portion 1 is projected from the under side through the under portion 9 of the tie, that is, the portion contiguous to the shirt, and through the under 60 portion 10 of the tie without being projected entirely through the latter. The pin portion 1 will remain in the position in which illustrated in Fig. 3 until withdrawn therefrom by hand, both on account of the engagement of the sinuous portion 5 with the fabric of the tie and on account of the fact that the portions of the tie through which the pin has been projected 65 are clamped at 6 between the pin portion 1 and the spring clamping portion 3. The U-shaped clamping loop 7 is then arranged with the arms thereof straddling an edge portion 11 of a shirt. Obviously, the edge portion 11 will be clamped between the arms 70 of the substantially U-shaped clamping loop 75 since these arms normally contact one another adjacent to their extremities.

When the pin portion 1 is projected into a four-in-hand tie intermediate its side edges, as illustrated, the outer portion of 80 the tie will cover the entire holder, which will be clamped in the manner described to the shirt and to the tie to maintain the tie in adjusted position with respect to the shirt without it being apparent to any one that a tie holder is being used. The device can be 85 readily applied and as readily detached without injuring either the tie or the shirt.

We claim:

1. A tie holder comprising a single piece 100 of wire formed to provide a pin portion, a clamping portion arranged to extend substantially at right angles to the pin portion and bent substantially into U-shape adjacent to its extremity, and a spring portion 105 merging the pin portion and the clamping portion one into the other.

2. A tie holder comprising a single piece 110 of wire formed to provide a substantially straight pin portion, said pin portion being sinuous adjacent to its end, a clamping portion bent into a substantially U-shaped loop

adjacent to its extremity, said loop being arranged to extend substantially at right angles to the pin portion, and a spring portion merging the pin portion and the clamping portion one into the other.

3. A tie holder comprising a single piece of wire having spring qualities and being formed intermediately to provide a spring portion merging a pin portion and a clamping portion one into the other, said clamp-

ing portion being arranged to normally contact the pin portion at a point about one-third the distance to its extremity and then being bent laterally of the pin portion and formed into a substantially U-shaped loop, 15 the arms of said loop being arranged to normally contact each other adjacent to their extremities.

GEORGE E. POTTER.
ELVIE L. POTTER.
